UNITED STATES PATENT OFFICE

2,428,107

FIRE ALARM

Albert Yohn, Buffalo, N. Y.

Application August 20, 1946, Serial No. 691,842

1 Claim. (Cl. 116—106)

1
This invention relates to improvements in fire alarms.

An object of the invention is to provide an improved audible fire alarm.

Another object of the invention is to provide an improved audible fire alarm in which a spring projected firing pin will be held in tensioned position by means of a bell crank lever trigger member and a suitable fusible link in position to fire a blank cartridge when said link is melted due to the heat from a nearby fire.

Another object of the invention is to provide an improved audible fire alarm signal which will include a slideable firing pin and an aligned blank cartridge holder, said firing pin being held in retracted position by means of a coil spring under tension, the same being held by a bell crank shaped trigger lever having a latch formed at its inner end and a fusible link secured between the same and a fixed support upon the fire alarm housing.

A further object of the invention is to provide an improved audible fire alarm consisting of a body member being formed with a plurality of spaced apertures serving as a sounding board, together with a blank cartridge holder and a spring projected firing pin held in cocked position by means of a strand of fusible metal wire, whereby when a fire gets too close to the fire alarm signal, the fusible link will melt, thereby releasing the spring tensioned firing pin which will be projected forwardly to engage the head of the blank cartridge to explode the same, giving a warning to persons in adjacent places that a fire is burning close by.

Another object of the invention is to provide an improved fire alarm signal formed with a cartridge holding box and a spring retracted firing pin adapted to engage the blank cartridge, and a perforated cover or sounding wall therefor.

Another object of the invention is to provide an improved audible fire alarm signal which will be highly efficient in operation, and relatively inexpensive to manufacture and produce.

Other objects will appear as the description proceeds.

In the accompanying drawings which form a part of this application,

Figure 1 is a front elevation of the perforated cover for the fire alarm signal;

Figure 2 is an edge view of the fire alarm signal;

Figure 3 is a front elevation of the fire alarm signal with cover removed;

Figure 4 is a sectional view taken on the line 4—4 of Figure 3, and

Figure 5 is a sectional view taken on the line 5—5 of Figure 3.

Like characters of reference are used throughout the following specification and the accom-

2
panying drawings to designate corresponding parts.

In carrying out the invention, there is provided an improved audible fire alarm signal having a base plate 1 preferably formed of metal and having an upstanding ear 2 along its central upper edge, said ear being perforated at 3 for supporting the signal upon a nail or hook (not shown).

A cartridge supporting block 5 is suitably mounted on the base plate 1, and is formed with a bore 6 in which a blank cartridge 7 may be inserted. An upstanding inwardly directed guard 8 will be disposed on the plate 1 slightly spaced in front of the block 5, to protect persons from injury or powder burns when the blank cartridge is fired.

Disposed upon the base plate 1 adjacent the block 5, is a guide block 9 through which the metal firing pin 10 is slidably mounted. The front end 11 of the firing pin 10 is bevelled off to provide a more-or-less pointed end for engagement with the firing cap in the face of the cartridge.

The adjacent side edge of the base plate 1 is rolled as at 12 to provide a cylindrical housing in which the head 13 on the rear end of the firing pin 10 is freely slideable, engaging one end of a coil spring 14, also mounted in the housing 12, the opposite end of the spring engaging the disc head 15 which is supported in place in said housing by the inwardly directed fingers 16 formed thereon.

A longitudinally extending slot 17 is formed between the lower end of the rolled housing 12 and said base plate 1, and is provided to receive the hooked end or trigger end 18 of the bell crank shaped trigger bar 19 pivotally supported upon the pin 20 on the upper surface of the base plate 1, to engage the forward surface of the head 13 to hold the firing pin 10 retracted against the tension of the coil spring 14.

A lug 21 extends upwardly from the base plate 1 to anchor the looped end of the fusible metal link 22, whose opposite end is looped over the adjacent end of the trigger bar 19 to hold said firing pin 10 cocked against the tension of the said coil spring 14.

A perforated cover 23 for the fire alarm signal is provided, the perforations 24 being provided to permit the ready egress of the sound to pass out of said fire alarm signal when the blank cartridge is fired. The cover 23 is further apertured at 25 through its edge to permit heat to reach the fusible link 22 to operate the fire alarm signal should 55 the heat rise above a predetermined point. The cover 23 further acts as a sounding board to increase and multiply the volume of sound emitted when the fire alarm signal is actuated.

From the foregoing description, it will be seen that since all parts of the fire alarm signal are

formed of metal, the fusible link 22 will be readily melted when the temperature of a room equipped with the improved fire alarm signal is increased sufficiently due to the presence of a nearby fire, thereby releasing the trigger bar 19, which in turn releases the spring tensioned firing pin to fire the blank cartridge.

Due to the construction of the fire alarm signal and the low cost of blank cartridges, the device may be installed and used over a long period of time with a minimum original expense and maintenance cost.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

An audible fire alarm signal including a flat base plate having a portion of one edge thereof rolled to form a tubular housing open at one end and formed with inwardly directed spring-supporting fingers on its opposite end, a coil spring seated on said fingers, a firing pin block on said base adjacent said housing, a headed firing pin slidably supported in said block with its head engageable with the adjacent opposite end of said coil spring, a cartridge block aligned with said

firing pin block and coil spring housing disposed upon said flat base, a blank cartridge in said cartridge block, the adjacent end of said flat base being bent upwardly and inwardly adjacent said cartridge block to provide a powder guard, a bell crank lever trigger pivotally supported on said flat base engageable with said firing pin head to compress said firing pin projecting spring when said trigger is in set position, an anchoring pin on said flat base, a fusible link supported by said bell crank trigger engageable with said pin for holding said firing pin in cocked position, and a perforated cover removably supported upon said flat base forming a sounding board and having an aperture extending through one edge thereof adjacent said fusible link for permitting heat to enter directly through said cover to melt said fusible link in case of fire.

ALBERT YOHN.
